United States Patent Office

Des. 227,100
Patented June 5, 1973

227,100

BATHTUB

Harold D. Weiss, 56 Dorian Way,
San Rafael, Calif. 94901

Filed Jan. 17, 1972, Ser. No. 218,646

Term of patent 14 years

Int. Cl. D23—02

U.S. Cl. D23—55

Fig. 1.

Fig. 2.

Fig. 3.

Fig. 4.

Fig. 5.

Fig. 6.

Fig. 7.

FIG. 1 is a front perspective view taken from the top of a bathtub showing the claimed design;

FIG. 2 is a top plan view thereof;

FIG. 3 is an elevation view thereof, looking from the left in FIG. 1;

FIG. 4 is a bottom plan view thereof;

FIG. 5 is a rear elevation view thereof;

FIG. 6 is an end elevation view thereof, looking from the right in FIG. 1; and

FIG. 7 is a front elevation view thereof.

I claim:

The ornamental design for a bathtub, as shown.
